UNITED STATES PATENT OFFICE.

LESLIE HOPKINS, OF KANSAS CITY, MISSOURI.

APPARATUS FOR PRODUCING AND CONTROLLING THE VACUUM IN STEAM-HEATING SYSTEMS.

1,152,634.

Specification of Letters Patent.

Patented Sept. 7, 1915.

Application filed August 11, 1914. Serial No. 856,228.

To all whom it may concern:

Be it known that I, LESLIE HOPKINS, a citizen of the United States of America, residing at Kansas City, in the county of Jackson and State of Missouri, have invented certain new and useful Improvements in Systems and Apparatus for Producing and Controlling the Vacuum in Steam-Heating Systems; and I do hereby declare that the following is a full, clear, and exact description of the invention, such as will enable others to make and use the same, reference being had to the accompanying drawings, forming a part of this specification.

The invention is related to apparatus for producing and maintaining a vacuum in the steam radiating pipes in steam heating systems, whereby the air resistance to the circulation of the steam is prevented, and the cost of steam production is minimized.

The principal objects of the invention are: First: to effect suction upon the air in the steam pipes by the direct action of the live steam, thereby dispensing with the ordinary pump. Second: to increase the efficiency of the service supply of live steam, for effecting the vacuum in the vacuum tank. Third: to obtain a vacuum in the vacuum tank automatically, and immediately following the breaking of the vacuum, and with increased steam supply efficiency when the steam pressure is below atmospheric pressure. Fourth: to control the delivery of the live steam to the vacuum tank, independently of steam-operated devices. Fifth: to obtain a uniform positive action of the water valve in vacuum tanks, when the pressure of the steam is diminished. Sixth: to control the action of the water and steam valve, by the water service pressure. Seventh: mechanism co-acting with a motor and steam-feeding system to automatically control the action of the motor, upon cessation of the flow of the steam. Eighth: means for controlling the intermittent action of combined water actuated and steam supply valves, for combined steam and water service systems; and ninth: to insure the adequacy of the supply of steam to the vacuum tank, in the action of the motor.

The invention consists in certain novel features of construction and combination of parts, which will be first fully described and then specifically pointed out in the claims,

reference being had to the accompanying drawings, in which like numerals of reference in all the figures thereof, indicate like parts.

Figure 1. is a view, in elevation, of a steam generating and heating plant embodying a vacuum tank, showing the invention applied thereto. Figs. 2. and 3. are rear and front views, respectively, of the novel apparatus, for producing and controlling the vacuum in the vacuum tanks. Fig. 4. is a plan view of the same. Fig. 5. is a vertical, longitudinal, sectional view, taken upon the line *x*, *x*, in Fig. 2. Fig. 6. is a transverse, vertical, sectional view, taken on the line *o*, *o*, on Fig. 4, looking in the direction of the water motor. Fig. 7. is a longitudinal, sectional view of the spring-controlled reproducing tube and shock absorber, taken on the line *y*, *y*, on Fig. 4. Fig. 8. is a vertical, 75 sectional view of the valve chamber for the water motor, taken on the line *z*, *z*, on Fig. 4, and showing the inlet pipe. Fig. 8^a. is a vertical, sectional view, taken through the water supply valve box, the valve casing showing the rotative or oscillating valve and valve stem controlled by the reciprocating tube, and taken on the line *l*, *l*, on Fig. 4. Fig. 9. is a view of the forward end of the valve chamber, showing the valve stem, and a sectional portion of the spring-retracted controlling bar, to which it is pivotally attached. Fig. 9^a. is a detail view of the pivoted end of the crank arm on the water valve, and a portion of the valve operating 80 bar. Fig. 10. is a detail view, in perspective, of the duplex steam cut-off piston valves, in the steam cylinder. Fig. 11. is a detail view, in perspective, of the inner, hollow cylinder for the piston valves in the steam cylinder, showing the ports and valve-guiding rib on the inner surface of the cylinder. Fig. 12. is a detail view of the oscillating water cut-off valve, in the valve casing on the water motor, and Fig. 13. is 85 the valve stem in said casing. Fig. 14. is a view, in perspective, of a form of thermostat, which may be employed as an alternate means for controlling the movement of the sliding bar which opens the water valve in 90 the water valve chamber. Fig. 15. is a detail view, in perspective, of the valve stem in the valve casing on the water motor, and Fig. 16. is a detail view, in perspective, of the valve stem in the valve casing on the water motor, and Fig. 17. is a detail view, in perspective, of the valve stem in the valve casing on the water motor, and Fig. 18. is a detail view, in perspective, of the valve stem in the valve casing on the water motor, and Fig. 19. is a detail view, in perspective, of the valve stem in the valve casing on the water motor, and Fig. 20. is a detail view, in perspective, of the valve stem in the valve casing on the water motor, and Fig. 21. is a detail view, in perspective, of the valve stem in the valve casing on the water motor, and Fig. 22. is a detail view, in perspective, of the valve stem in the valve casing on the water motor, and Fig. 23. is a detail view, in perspective, of the valve stem in the valve casing on the water motor, and Fig. 24. is a detail view, in perspective, of the valve stem in the valve casing on the water motor, and Fig. 25. is a detail view, in perspective, of the valve stem in the valve casing on the water motor, and Fig. 26. is a detail view, in perspective, of the valve stem in the valve casing on the water motor, and Fig. 27. is a detail view, in perspective, of the valve stem in the valve casing on the water motor, and Fig. 28. is a detail view, in perspective, of the valve stem in the valve casing on the water motor, and Fig. 29. is a detail view, in perspective, of the valve stem in the valve casing on the water motor, and Fig. 30. is a detail view, in perspective, of the valve stem in the valve casing on the water motor, and Fig. 31. is a detail view, in perspective, of the valve stem in the valve casing on the water motor, and Fig. 32. is a detail view, in perspective, of the valve stem in the valve casing on the water motor, and Fig. 33. is a detail view, in perspective, of the valve stem in the valve casing on the water motor, and Fig. 34. is a detail view, in perspective, of the valve stem in the valve casing on the water motor, and Fig. 35. is a detail view, in perspective, of the valve stem in the valve casing on the water motor, and Fig. 36. is a detail view, in perspective, of the valve stem in the valve casing on the water motor, and Fig. 37. is a detail view, in perspective, of the valve stem in the valve casing on the water motor, and Fig. 38. is a detail view, in perspective, of the valve stem in the valve casing on the water motor, and Fig. 39. is a detail view, in perspective, of the valve stem in the valve casing on the water motor, and Fig. 40. is a detail view, in perspective, of the valve stem in the valve casing on the water motor, and Fig. 41. is a detail view, in perspective, of the valve stem in the valve casing on the water motor, and Fig. 42. is a detail view, in perspective, of the valve stem in the valve casing on the water motor, and Fig. 43. is a detail view, in perspective, of the valve stem in the valve casing on the water motor, and Fig. 44. is a detail view, in perspective, of the valve stem in the valve casing on the water motor, and Fig. 45. is a detail view, in perspective, of the valve stem in the valve casing on the water motor, and Fig. 46. is a detail view, in perspective, of the valve stem in the valve casing on the water motor, and Fig. 47. is a detail view, in perspective, of the valve stem in the valve casing on the water motor, and Fig. 48. is a detail view, in perspective, of the valve stem in the valve casing on the water motor, and Fig. 49. is a detail view, in perspective, of the valve stem in the valve casing on the water motor, and Fig. 50. is a detail view, in perspective, of the valve stem in the valve casing on the water motor, and Fig. 51. is a detail view, in perspective, of the valve stem in the valve casing on the water motor, and Fig. 52. is a detail view, in perspective, of the valve stem in the valve casing on the water motor, and Fig. 53. is a detail view, in perspective, of the valve stem in the valve casing on the water motor, and Fig. 54. is a detail view, in perspective, of the valve stem in the valve casing on the water motor, and Fig. 55. is a detail view, in perspective, of the valve stem in the valve casing on the water motor, and Fig. 56. is a detail view, in perspective, of the valve stem in the valve casing on the water motor, and Fig. 57. is a detail view, in perspective, of the valve stem in the valve casing on the water motor, and Fig. 58. is a detail view, in perspective, of the valve stem in the valve casing on the water motor, and Fig. 59. is a detail view, in perspective, of the valve stem in the valve casing on the water motor, and Fig. 60. is a detail view, in perspective, of the valve stem in the valve casing on the water motor, and Fig. 61. is a detail view, in perspective, of the valve stem in the valve casing on the water motor, and Fig. 62. is a detail view, in perspective, of the valve stem in the valve casing on the water motor, and Fig. 63. is a detail view, in perspective, of the valve stem in the valve casing on the water motor, and Fig. 64. is a detail view, in perspective, of the valve stem in the valve casing on the water motor, and Fig. 65. is a detail view, in perspective, of the valve stem in the valve casing on the water motor, and Fig. 66. is a detail view, in perspective, of the valve stem in the valve casing on the water motor, and Fig. 67. is a detail view, in perspective, of the valve stem in the valve casing on the water motor, and Fig. 68. is a detail view, in perspective, of the valve stem in the valve casing on the water motor, and Fig. 69. is a detail view, in perspective, of the valve stem in the valve casing on the water motor, and Fig. 70. is a detail view, in perspective, of the valve stem in the valve casing on the water motor, and Fig. 71. is a detail view, in perspective, of the valve stem in the valve casing on the water motor, and Fig. 72. is a detail view, in perspective, of the valve stem in the valve casing on the water motor, and Fig. 73. is a detail view, in perspective, of the valve stem in the valve casing on the water motor, and Fig. 74. is a detail view, in perspective, of the valve stem in the valve casing on the water motor, and Fig. 75. is a detail view, in perspective, of the valve stem in the valve casing on the water motor, and Fig. 76. is a detail view, in perspective, of the valve stem in the valve casing on the water motor, and Fig. 77. is a detail view, in perspective, of the valve stem in the valve casing on the water motor, and Fig. 78. is a detail view, in perspective, of the valve stem in the valve casing on the water motor, and Fig. 79. is a detail view, in perspective, of the valve stem in the valve casing on the water motor, and Fig. 80. is a detail view, in perspective, of the valve stem in the valve casing on the water motor, and Fig. 81. is a detail view, in perspective, of the valve stem in the valve casing on the water motor, and Fig. 82. is a detail view, in perspective, of the valve stem in the valve casing on the water motor, and Fig. 83. is a detail view, in perspective, of the valve stem in the valve casing on the water motor, and Fig. 84. is a detail view, in perspective, of the valve stem in the valve casing on the water motor, and Fig. 85. is a detail view, in perspective, of the valve stem in the valve casing on the water motor, and Fig. 86. is a detail view, in perspective, of the valve stem in the valve casing on the water motor, and Fig. 87. is a detail view, in perspective, of the valve stem in the valve casing on the water motor, and Fig. 88. is a detail view, in perspective, of the valve stem in the valve casing on the water motor, and Fig. 89. is a detail view, in perspective, of the valve stem in the valve casing on the water motor, and Fig. 90. is a detail view, in perspective, of the valve stem in the valve casing on the water motor, and Fig. 91. is a detail view, in perspective, of the valve stem in the valve casing on the water motor, and Fig. 92. is a detail view, in perspective, of the valve stem in the valve casing on the water motor, and Fig. 93. is a detail view, in perspective, of the valve stem in the valve casing on the water motor, and Fig. 94. is a detail view, in perspective, of the valve stem in the valve casing on the water motor, and Fig. 95. is a detail view, in perspective, of the valve stem in the valve casing on the water motor, and Fig. 96. is a detail view, in perspective, of the valve stem in the valve casing on the water motor, and Fig. 97. is a detail view, in perspective, of the valve stem in the valve casing on the water motor, and Fig. 98. is a detail view, in perspective, of the valve stem in the valve casing on the water motor, and Fig. 99. is a detail view, in perspective, of the valve stem in the valve casing on the water motor, and Fig. 100. is a detail view, in perspective, of the valve stem in the valve casing on the water motor, and Fig. 101. is a detail view, in perspective, of the valve stem in the valve casing on the water motor, and Fig. 102. is a detail view, in perspective, of the valve stem in the valve casing on the water motor, and Fig. 103. is a detail view, in perspective, of the valve stem in the valve casing on the water motor, and Fig. 104. is a detail view, in perspective, of the valve stem in the valve casing on the water motor, and Fig. 105. is a detail view, in perspective, of the valve stem in the valve casing on the water motor.

15 indicates a steam generating upright boiler, of well-known construction, and 16 indicates the delivery pipe therefrom, which, as shown, extends upwardly and is connect- 110

ed with the outer end portion of a pipe 17, of reduced diameter, in which is an ordinary steam cut-off valve 18.

20 indicates an ordinary steam circulating 5 heat radiator, with the base 19, of which the inner end of the pipe 17 is connected.

21 indicates the air pipe leading from the radiator, the upper end of which terminates near the line of the top of the radiator, and with which end is connected an ordinary thermostat valve 22, which automatically closes when the live steam reaches the valve, and raises the temperature of the radiator. With the thermostat valve casing 15 is connected a short pipe 23, which is also connected with the upper portion of the radiator.

24 indicates a hermetical vacuum-producing tank for the rapid condensation of live 20 steam, and the consequent production of a vacuum which acts as subsequently referred to, to draw the air from the radiator or radiators at all times when the thermostat valve is open.

25 With the bottom plate 25, of the tank 24, is connected the upper end portion of a U-shaped pipe 26, which acts as a trap for the water of condensation, and in the inner end of the pipe is a check valve 27. A short pipe 30 extends through the vertical wall plate of the tank 24, at a point a short distance below the line of the horizontal top plate 30, of the tank for the outward expansion of the air, and in said pipe is a check valve 35 29. A three-way pipe connection 31, at the outer end of pipe 28, is connected by means of a vertical pipe 32, with a three-way pipe connection 33, on the outer end of the extension of the U-shaped pipe 26, from which 40 connection 33, a pipe 34 extends, to a suitable basin or sewer.

Downwardly through the central portion of the top plate 30, of tank 24, extends the water cock 35, a flange 36 thereon being 45 hermetically secured to the top plate. The valve stem 37, in the upper end of the cock 35 is shown in Fig. 5, and with the stem is connected a short crank arm 38, which is operated as hereinafter described. In order to 50 cause a spray of the water discharged within the tank, a perforated upwardly-curved plate 39 is suspended beneath the inner end of the cock 35, by the depending rods 40, the water discharged from the cock being 55 sprayed upon the inner surfaces of the tank and through said perforated plate. The supply of water to the cock 35 is through the pipe 41, leading from the street water service pipe, the inner end of which pipe is connected with the outer end of the cock adjacent 60 the valve stem, as seen in Fig. 1.

The outer end portion of the air-conducting pipe 21, connected with the radiator 20, extends to and is connected with a four-way pipe joint connection 42, upon the up-

per surface of the top plate 30, of the vacuum tank, and in said pipe 21 is a check valve 43. The pipe connection 42, for the purpose hereinafter mentioned, is of large capacity. One opening in the said connection opposite the entrance of the air pipe 21, is closed by a plug 44, and connected with said plug is an arm 45, the outer end portion 46 of which is bent at right angles and extended in an upward direction, for the 75 purpose further described.

A steam conducting pipe 47 is connected with the lower opening in the pipe connection 42, and extends downwardly through the top plate 30, of the vacuum tank, at a 80 point intermediate the position of the cock 35 and the vertical side plate of the tank 24, the lower end of the pipe terminating at a point approximately one-half the distance 85 downwardly from the line of the top plate 30, in the direction of the bottom plate 25, of the tank.

The discharge of the steam and air within the vacuum tank, followed by the spray of water, produces a rapid condensation of 90 the steam and a pump action or suction upon the air, in the air pipe 21, caused by the vacuum formed in said tank, to control and maintain which vacuum a combined motor and steam supply regulating apparatus 95 50 is arranged in position above the upper surface of the top plate 30, of the vacuum tank, and supported thereon, the details of construction of which being now specifically referred to. This apparatus consists mainly 100 of a hydraulic motor 48, and a steam cut-off and supply piston valve device 49, which is actuated by the motor. The hydraulic motor consists of the hollow body cylinder 51, hermetically closed by the outer and inner end plates 51^x 51°, respectively, within which are the cup-shaped pistons 52, 53, reversed in position and mounted fixedly upon the inner end of the piston rod 54, as seen in Fig. 5. Upon the upper surface of the cylinder and supported by the bracket 55, is a circular valve casing 56, the bracket being a part of and located upon one side of the casing. Within the casing is a circular valve chamber 57, extending transversely thereto and in the direction of the lower portion of the casing and eccentric thereto. Within the casing are two ports 58 and 59, extending in opposite directions upwardly and in radial lines from the center of the chamber. Connected with these ports are the water conducting pipes 60 and 61, respectively, which extend downwardly in the direction of and connected with the respective ports 62 and 63, in the upper portion and respective outer and inner ends of the cylinder 51.

110 In the bracket 55 is an opening 64, larger in circumference than the chamber 57, as seen in Fig. 8^a, and extending through said opening is an externally screw- 115 120 125 130

threaded shoulder 65, on the outer surface of the valve casing. With the shoulder 65 is connected an internally screw-threaded thimble 66, which bears hermetically against the outer surface of the bracket. Upon the reverse side of the valve casing is a laterally extended shoulder or extension 67, formed integral therewith, through which extends an opening 68, of reduced size to that of the chamber 57, and to which shoulder is connected, by means of a nipple 69, the valve box 70, having a chamber 70^x, the nipple extending within an opening 71, in the inner side wall 72, of the box, adjacent the upper end thereof, as seen in dotted lines in Fig. 8. Upon the outer portion of the valve box 70 is an annular, externally-screw-threaded extension 73, having an opening 74, in line horizontally with the opening 71, and upon said extension is an internally screw-threaded stuffing box 75, through which extends a rotary valve stem 76, upon the inner end of which stem is fixed a depending valve block 77, upon the lower end and outer face portion of which is an insert or block 78, composed preferably of rubber. Within the lower portion and outer wall 70^x of the valve box 70, extends the inner end of a nipple 79, the opening in which is directly opposite the rubber insert 78, on the valve 77, and normally closed thereby. A supply pipe 80, for water under pressure, is connected with the outer end portion of the nipple 79, and its outer portion is bent at right angles and extended downwardly and connected at 81 with the water service and supply pipe 41, as seen in Fig. 1. In the supply pipe 80 is a cut-off valve 82.

The exhaust port 83, for the water from the valve casing 56 (see Fig. 5) is located in the upper portion thereof, at a point equidistant from the ports 58 and 59. With the port 83 is connected one end of a water conducting pipe 84, the outer end portion 85 being bent at right angles and extended downwardly and connected with the three-way pipe connection 31, through which the air is discharged from the vacuum tank. The valve 86, for the valve chamber 57, 50 consists of a spring plate, bent to form a longitudinally split hollow cylinder, the ends of the plate being separated by the opening 86^x, a slight distance, for retaining a close frictional contact with the inner surface of the chamber 57, as seen in detail in Fig. 12. The cylindrical valve 86 is provided with the ports 87 and 88, in opposite positions and transverse to the longitudinal axis of the cylinder, and with a groove 89, 60 constituting another port, in the upper portion of the cylinder, the forward ports being adapted to come into position with the ports 58 and 59, alternately, and the grooved port 89, which is in the arc of the circle of the outer circumference of the cylinder, extends in a transverse direction to the cylinder and being adapted to open communication with the ports 83 and 58 and 59 and 83, for the alternate discharge of the liquid. The valve cylinder 86 is provided with a plate 90, extending within one end of said cylinder, and secured thereto in a plane diametrically to the cylinder and beneath the opening 86^x. In said plate 90 is a longitudinal slot 91, extending three-fourths the length of said plate, to permit of the expansion of the cylinder 86 against the inner surface of the chamber 57.

A valve stem 92 operates the valve 86, having a longitudinal groove 93, at its inner end seen in Fig. 13, within which the outer end portion of plate 90 is secured. This stem 92 extends through the thimble 66, on the shoulder 65, on the valve casing 56, and through a stuffing box 93, on the outer end portion of said thimble, and upon the outer end of said stem is a depending crank arm 94, in which is a longitudinal slot 95, for the purpose further explained.

A crank arm 97 (see Fig. 9), which is connected at its upper end rigidly with the valve stem 76, extends downwardly, approximately a slight distance below a line horizontal with the lower surface of the bottom of the valve box 69, and a portion 98^x is bent at right angles and extended inwardly in the direction of and adjacent said cylinder, and a short portion 98^y bent upwardly at 99, as seen in Fig. 9, to which portion is pivotally and loosely connected, at 99^x, one end of a longitudinally movable valve-operating and motor-actuating bar 100. A plate 101, rigidly connected with the vertical outer surface of the rear end 70^y, of the valve box 69, extends downwardly below the line of the bottom of said box, and is provided with a transverse opening 102 (see Fig. 8), through which the said sliding bar 100 extends. Extending around the bar 100 is a coiled, expansible spring 103, which bears upon the inner surface of the plate 101 and against a fixed lug 104, on said bar, the spring 103 acting, when compressed, to expand and open the valve 77, in the valve box 70.

The steam valve device 40 consists of a hollow cylinder 105, closed hermetically by the respective outer and inner end plates 106, 107, bolted to the outwardly-extended flanges of the cylinder, as shown, the circumference of which is the same as the cylinder 56, of the hydraulic motor.

Parallel connecting plates 108 and 109, of the requisite length, are connected integrally with the outer surfaces of the end plates 51^y and 107, of the respective cylinders 51 and 105, said plates being spaced apart in a vertical position, the requisite distance. Within the cylinder 105 is a valve-carrying cylinder 110, which is approximately one-half

the circumference of the outer cylinder 105, which cylinder 110 is provided with outwardly-extended flanges 110^x, which are secured to the inner surfaces of the outer and 5 inner plates 106 and 107 by the bolts 111. Ports 112, 113 and 114 are made in the cylinder 110, the openings being in the direction of the circumference of said cylinder and spaced equal distances apart, and located intermediate the ends of said cylinder 10 10 (see Fig. 11).

The duplex valves, which act to regulate the admission of the steam to the vacuum tank, consists of separate cylindrical spring 15 plates 115 and 116, the ends being separated by a slight space, as seen at 115^x and 116^x, of the respective plates, the plates being slightly compressed, and therefore under tension when the plates are inserted within 20 the cylinder 110 (see Fig. 10). Centrally perforated bars 117, 118, in the respective cylindrical plates 115 and 116, are connected at their ends with the inner surfaces of the plates, and upon one side of the respective 25 openings 115^x, 116^x, and extend diametrically to the plates therefrom, and rotatable therein. The bars 117 and 118, supporting the valves are mounted on the inner end portions of a valve stem 119, the valve-supporting 30 bar 118 being fixed rigidly on said stem, at a point inwardly from the outer end of said stem, to permit of the stroke from the position of the ports 112 and 113, to the end plate 107, of the cylinder. The valve-supporting 35 bar 117 is loosely mounted on the valve stem, and at the outer end of said stem is a retaining nut 120. In the stroke of the cylindrical valve 116, toward the end plate 107 of the cylinder, the cylindrical valve 115 40 is moved by the contact with nut 120, thereby closing the ports 112, 113 and 114, while a movement of the valve 116 in a reverse direction the valves contact with each other and move in unison, to complete the stroke 45 and keeping the ports 112, 113 and 114 closed. Between the cylinders 105 and 110 is formed a circular chamber 121. In the lower portion of the cylinder 105 is an opening 122, in communication with the steam 50 expanding chamber 121, within the cylinder 105, extending around the cylinder 110, in which opening is fitted a short length of pipe 123, the lower end of said pipe being fitted to the four-way pipe connection 42, 55 into which the air pipe 21 from the radiator 20 extends. The outer end plate 106, of the cylinder 105, is provided with an opening 124, for the entrance of the steam, and of the same inner circumference as the cylinder 60 110. A flange 125, upon the outer surface of said end plate extends around said opening, and is internally screw-threaded, and fitted to said flange is an externally screw-threaded end of a short pipe 126, with 65 which pipe is connected a three-way pipe

connection 127. An independent pipe 128 is connected with the pipe connection 127, which extends to and is connected at 128^x, to a three-way pipe connection in the supply pipe 16, leading from the steam generator 70 to the radiator 20 (see Fig. 1). In the pipe 128, adjacent the pipe connection 127, is a cut-off valve 130. A pipe 131, connected at its lower end with the pipe 128, is provided with a gage 132, at its upper end, which registers the degrees of steam pressure at the generator 15. A pipe 133 is also connected at its lower end with the top plate 30, of the vacuum tank, and with its upper end is connected a gage 134, which indicates the force 80 of the vacuum within the tank 24.

The means for steam valve control in the cylinder 110 is as follows: The inner end of the valve stem 119 extends through the inner end plate 107, of cylinder 105, and through the stuffing box 135, and the inner end of the piston rod 54, in the hydraulic cylinder 51 extends through the end plate 51^x and the stuffing box 136, on said end, the said ends of the piston rod and valve stem being screw-threaded and connected with the screw-threaded opening 138, extending transversely through the reciprocating cross-head or block 137, with the lateral surface of which block are connected integrally the 90 wing or guide plates 139, the outer surfaces of which plates move reciprocally upon the longitudinal, frictional surfaces of the plates 140, which are bolted to the inner surfaces of the connecting plates 108, 109, for the cylinders 51 and 105 (see Fig. 6). A tube 141, located directly beneath and in vertical lines with the outer ends of the piston rod 54 and stem 119, is connected at its ends rigidly with the lower portions of the respective end plates 51^x and 107, of the cylinders 51 and 105, in the upper surface of which is a longitudinal opening 142, extending from a position a short distance from the end connected with the end plate 107, to the opposite end of said tube. In the lower portion of the tube is a longitudinal opening 143, extending from the line of the outer surface of end plate 51^x, about one-third the distance toward the end plate 107, of cylinder 105 (see Fig. 5). A reciprocating plate 144 extends upwardly through the opening 143 and to the line of the opening 142, and a forward, curved locking projection or catch-pin 145 extends from the upper surface of said plate 144, in line with its vertical surface, in the direction of the end plate 51^x, of cylinder 51. A longitudinal stem 146 is connected with the reverse surface of the plate 144, the outer end extending a considerable distance within the tube 141, in the direction of the end plate 107, of cylinder 105, and upon said end is a head or knot 147. A sliding lug 148 is mounted loosely on the outer end of the 125 130

stem 146, a short distance from its end, in the upper surface of which lug is a depression or opening 149. A coiled compression spring 146* extends around the stem 146, one end bearing against the plate 144, and the other end against the lug 148. An arm 150 is connected with the lower portion of the head block 137, which is bent a short distance therefrom and extended horizontally in the direction of the end plate 107, of the cylinder 105, and to a point above the lug 148, in tube 141, and a portion 151 extended downwardly within the opening 149, in said lug. Extending from and in opposite directions to the arm 150 is a trip plate 150*.

152 indicates a hinged stop or catch plate for the reciprocating plate 144, which is located directly beneath the stuffing box 136, for the piston 54, and extends transversely to the upper surface of the tube 141, the ends of said plate having upward extensions 153, which are pivotally connected with the inner surfaces of the respective connecting plates 108 and 109 to the cylinders 51, and 105 (see Figs. 4 and 6). The lines of the free end of catch plates 152 are reduced or curved inwardly, as seen in Fig. 4, and upon the lower surface of said end is a catch pin 154, which is in the path of travel of the projection or pin 145, on the upper surface of the plate 144. A flat spring plate 155 bears upon the upper surface of the catch plate 152, the inner end portion of which spring plate is secured to the lower surface of the stuffing box 136.

40 A lever arm 156, having a forked upper end, is pivotally connected with the lower end portion of the reciprocating plate 144, with the central portion of which arm is connected pivotally a link 157, said links also being pivotally connected with upper end portion 46, of the arm 45, on the plug 44, on the pipe connection 42, for the steam 45 and air. A link 158 is also pivotally connected with the lower end of the bar 156, and with the upper end portion of the crank arm 38, on the valve stem 37, of the water supply cock 35, in the top 30, of the vacuum 50 tank. Directly above the cylinder 105, and supported by the standard 160 is a thermodynamic regulator, consisting of a hermetical vessel or receiver 161, for the live steam. A supply pipe 162 extends at one 55 end within the receiver and through the bottom plate 163, a slight distance, in which are inlet openings 164 (see Fig. 5). The other end of the pipe 162 is connected with an elbow 164, which elbow is in steam connection with the three-way pipe connection 60 127, through the plug 165, in one of the openings in the side of said pipe connection.

65 A volatile liquid container 166 is arranged within the steam receptacle 161, which is provided with hermetically connected con-

cave top and bottom plates or heads 167 and 168, respectively, the latter plate 167 resting upon the blocks 169, on opposite sides of the upper portion of the steam pipe 162, extending within the receiver. A plunger rod 70 170 is connected with the central portion and upper surface of the top plate 167, and extends upwardly through the top plate 171, of said receiver and through a stuffing box 172, and is forked at said ends and pivotally 75 connected with a transverse bar 173, which bar is pivotally connected at 174, with the upper end portion of a vertical bar 175, extending a considerable distance above the line of the top plate 171, of the receiver, its 80 lower end being rigidly connected with the inner surface of said receiver (see Fig. 2).

Extending around the plunger rod 170 is a spiral compressible spring 176, the upper end of which spring bears against the inner 85 surface of the top plate 171, and the lower end upon the upper surface of the top plate or head 167, of the container.

The free end of the bar 173 extends to a position above the end portion of the longitudinal bar 100, connected with the valve operating crank arm 97, adjacent the cylinder 105. A downwardly extended bar 177 is pivotally connected at its upper end with the free end of the bar 173, and its forward 90 end extended downwardly through the outwardly-extended guide flanges 178, 179, on the vertical plate 180, connected with the receiver 161, the lower end of said bar being 95 provided with an opening 181, through 100 which the bar 100 extends.

The container 166 is supplied with a liquid, which when subjected to the heat from the steam expands, and consequently forces the heads 167 and 168 outwardly, 105 raising the plunger rod 170 and compressing the spring 176, and raising the rod 180 and the free end of bar 100. The liquid employed is alcohol, although other expandible volatile liquids may be used. Upon the 110 outer surface of the bar 100, approximately intermediate the guide bar 101 and the depending bar 177, is a flat stop plate 182, which extends a short distance below the line 115 of the lower surface of said bar, for the purpose further explained.

The means for controlling the action of the motor when the force of the vacuum in the vacuum tank diminishes, consists of a longitudinal reciprocating tube 185, located upon the rear or reverse side of the cylinders 51 and 105 to that having the valve-operating bar 100 (see Figs. 4 and 7). The tube 185 is supported by and movable within the encircling guide brackets 183 and 184, secured to the periphery of the end plates 51° and 107, of the respective cylinders 51 and 105, at a point on said periphery a short distance below a line horizontal with the upper surface of the connecting plate 109, for the re- 120 125 130

spective cylinders. The ends of the tube are movable within the shock-bearing cylindrical sockets 186, 187, and, of increased circumference to the tube 185, as seen in section in Fig. 7, in contact with the plunger 188, carried by the guide pins 189. Coiled springs 190, extending around the pins, bear against the inner surface of the plungers and the ends of the sockets, the pins 189 extending through the said ends and being provided with heads 191. The ordinary dash pot may, however, be substituted for the spring-recoiled plungers, if preferred. Sockets 186 and 187 are held fixedly in position by the brackets 192, secured rigidly thereto and to the outer plate 106, of the cylinders 105, and also to the flange on the cylinder 51, respectively.

In the ends of the tube 185, which are internally screw-threaded, are the screw-threaded plugs 193, 194, each plug having a head 195, which closes against the end portions of the tube. A longitudinal reciprocating plunger 196 is located within the tube 185, having circumferentially reduced outer end portions 197, upon the ends of which portions are the fixed caps 198. Spiral springs 199 and 200 are inserted within the tube 185, of the same length and expansibility, one end of the spring 199 bearing against the cap 198, at one end of plunger 196, and the other end against the cap 193, and the ends of spring 200 bearing against the cap 198, at the other end of the plunger 196 and the cap 195, in tube 185, respectively.

In the central portion of the plunger 196 is a transverse opening 201 (see Fig. 7). The connecting plate 109, at 109^x, and also the inner surface of the tube 185 opposite the opening 201 in the plunger, are provided with a longitudinal opening 202 (see Fig. 6), of the length to afford the reciprocations of the plunger. A flat bar 203 is secured at its inner end to the upper surface of the head block 137, the other end extending transversely thereto and within the opening 202, on the tube 185, and also within the opening 201, in the plunger 196, in the said tube. Upon the upper surface of the head block and plate 203 is secured the inner end of a bar or arm 204 (see Fig. 6), the other end of which bar extends to within a short distance of the inner surface of the connecting plate 108, to the cylinders, thence bent in an upward direction above the line of the upper surface of said plate, thence transversely thereto and extended in the path of the top plate 182, on the valve-controlling bar 100.

An upright power-transmitting bar 205 is provided with a collar 206, at its lower end, which extends around the reciprocating tube 185, adjacent the inner end of the shock-absorbing socket 187, said collar having a set screw 207, securing the collar to

the tube. A pin on the outer surface and upper end of bar 205 enters the slot 95, in the crank arm 94, on the valve stem 76, controlling valve 77, in the valve box 70.

In order to hold the tube 185 from a recoil movement incident to the compression of either spring 199 or 200, within the tube, two narrow plates 208 and 209 (see Fig. 4), are pivotally connected at their outer ends to the upper surface of the horizontal rib 109^x, on the outer surface of the connecting plate 109. Upwardly-extending pins 210 are connected with the upper surface and outer ends of these plates 208 and 209, the said ends of the plates being yieldingly held from inward movement by the coiled springs 212, 213, bearing at one end against the inner surface of said ends and also against the outer surface of plate 109. These plates are tripped in the alternate reciprocal movements of the tube 185, by means of plate 214, secured to the upper surface of the bar 203, on the cross-head 137, the inner surfaces of which extend from each end toward the bar 203, in inwardly-curved lines, as seen in Fig. 4.

Upon the outer surfaces and end portions of plates 208, 209 are catch pins 215 and 216, respectively, the outer surfaces being outwardly curved. Upon the reciprocating tube 185 are fixed collars 217 and 218 (see Fig. 2), upon the portions of which opposite the yielding plates 208, 209 are the catch pins 219, 220, respectively, whose surfaces are similar, but curved in a manner to readily move over the curved surfaces of the stop pins 215 and 216. The collars 217, 218 are arranged on the tube 185, between the brackets 183 and 184, and spaced apart the requisite distance and short distances from the respective brackets, and in the reciprocations of the tube moving in close position to the respective brackets. A collar 221, fixed to said tube and movable within a short distance of the outer surface of the bracket 183 in the reciprocation of the tube 185, is provided on its lower surface with a catch-pin 221^x (see Fig. 2).

222 indicates the controlling lever for the apparatus and the movement of the hydraulic motor, consisting of a horizontal bar pivoted at a point intermediate its ends to the outer end portion of a bracket or bar 222^x (see Fig. 4), which is connected at its inner end rigidly with the outer surface of the connecting plate 109, for the cylinders 51, 105, immediately below the rib 109^x, as seen in Fig. 6. One end of the lever 222 extends a short distance past a vertical line extending through the outer surface of the guide bracket 183, for the tube 185, and is halved at 223, inwardly from the end, and provided with an outwardly curved catch-pin 222^x, which comes into engagement with the catch-pin 219, in the collar 218, on tube 130

185, in the manner further described. The other end of lever 222 extends to a position in a vertical line with the bracket 184, supporting said tube.

5 225 indicates the vacuum controlled collapsible governor (see Figs. 3 and 7), which consists of a cup-shaped vessel 226, having outward flanges 227, upon which is seated a thin diaphragm 228, covering said vessel.

10 A circular plate or ring 229 extends upon the upper surfaces of the diaphragm and is bolted to said flanges 227 by the bolts 229*, passing through the outer portions of the diaphragm, which is composed of a yielding 15 material, such as rubber cloth, or maybe a thin metallic plate, as preferred.

A bracket, having a top plate 230, is provided with downwardly-extended portions 231, extending toward the diaphragm 228, 20 and their ends bent at right angles and secured to the ring 229 and diametrically thereto. Through a perforation in the top plate 230, of the brackets, extends one end of a rod 232, the lower end of said rod extending through the center of the diaphragm and provided with a fixed cap 233, which bears upwardly on the inner surface of said diaphragm. The upper end of the rod 232 is screw-threaded and provided with 25 an adjusting nut 234, on the portion of the rod beneath the top plate 230.

30 235 is a coiled compression spring, extending around the rod 232, one end of which bears on the upper surface of the diaphragm and the other end against said nut.

35 With the outer end of the rod 232 is connected a cap 236, having forked plates 237, pivotally connected with the adjacent end of lever 220, a slight distance inwardly from 40 its end, so as to bear on the cap, in its movement downwardly. The cup-shaped vessel 226 is supported by the outwardly-extended perforated horizontal plate 238, which is connected at 239 (see Fig. 3) with a bracket 45 240, secured at its rear end to the outer surface of the end plate 51°, of the cylinder 51.

In the lower portion of the vessel 226 is an opening 239 (see Fig. 7), and with said opening is connected the upper end of a pipe 50 241, which extends through the perforation 23, in the plate 238, the lower end of which pipe extends within the top plate 30, of the vacuum tanks 24 (see Fig. 1).

55 In operation, steam as generated passes through the pipe 128, to the steam valve cylinder 110, upon the opening of the valve 130, and water under its pressure, which is usually of hydraulic efficiency in the street service supply, is admitted from the supply 60 pipe 41 to the pipe 80, leading to the valve chamber in the valve box 70, upon the opening of the cut-off valve 82. In the position shown, of the operative parts of the apparatus, the piston 52, of the hydraulic motor, 65 is at the end of an outward stroke, hence

the inner valve 116, of the duplex valves is at the end of the inner stroke, the steam having been admitted through the ports 112, 113, preceding such movement, the other valve 115 being moved over, and now closing the steam ports 112, 113, in the valve cylinder 110. The temperature of the live steam in the receiver 161, which has entered from the pipe 162, has expanded the volatile fluid within the container, and consequently the plunger rod 170 has moved upwardly and compressed the spring 176 and raised the bar 177, and by it the free end of the sliding valve-operating bar 100 raising the stop plate 182 from contact with the arm on bar 204, on the reciprocating head block and permitting the previously compressed spring 103 to expand and move the valve-operating crank arm into the position seen in dotted lines in Figs. 1 and 2, 70 80

85 and opening valve 77, the water passing through the opening 71, in the valve box 70, to the valve chamber 57, in the valve casting 56. Coincident with the movement of the cross head 137, in the direction of the 90

cylinder 51, to effect the outward stroke of the piston 52, the spring 199, in the tube 185, has been compressed by the plunger 196, and the end of the reciprocating tube 185, in the direction of the shock-absorbing 95

socket 187, has moved with great force within the socket and the shock absorbed, the catch pin 220, on the collar 218, having passed the catch-pin 216, on the yielding 100

bar 209 and engaged with said pin and the catch pin 219 on collars 217, engage with pin 215, on the yielding bar 208, hence a reverse movement of the tube 185 is checked. The arm 150, on the cross-head 137, in this 105

movement, has compressed the spring 146*, thereby moving the sliding plate 144 to the end of tube 141, in the direction of cylinder 51, the catch plate 152* having been raised by the trip plate 150*. In this position of the plate 144, the upper end of the pivoted 110

bar 156 is moved outwardly and the lower end inwardly, and the crank arm 38, on the valve stem 37, is moved into the position as seen in full lines in Figs. 1 and 2, opening the valve 37, for the entrance of the water from the water service and supply pipe, to the cock, the water passing through the cock is sprayed, as before described. The live steam which has been admitted to the vacuum tank 24, has passed through the 115

pipe connection 42, from the chamber 121, in the cylinder 105, in which the steam expands into the vacuum tank, and the sprayed water within the tank has condensed the steam, forming a partial vacuum therein. 120 The movement of the reciprocating tube 185 into the position as described, has acted to move the crank arm 94 on the rotative valve 186 into a position to cut off the water pressure, and admit the water through port 130

58, bringing the grooved port and exhaust port in the casing into communication, and the water entering the pipe 60 exerts its pressure against the cylinder 52, hence, as 5 the piston begins an inward movement in the direction of the end plate 51°, of the cylinder 51, the water is discharged from the rear of piston, through the pipe 61, and the single groove port 89, in the valve 86, 10 with which it comes into communication, and the water is discharged through the pipe 84, thence through pipe 34 into the sewer. Upon the movement of the cross-head 137, in the direction of the cylinder 105, and 15 at the moment the trip bar 214, on the cross bar, strikes the pin 210, on the yielding plate 208, the inward movement of said plates releases the catch pin 215, on said plate, and the pin 219, on the collar 217, 20 on the tube 185, consequently the spring 199, in said tube, previously compressed, expands, forcing the reciprocating tube in the direction of the shock-absorber 186, thereby moving the crank arm 94 into the 25 dotted position as seen in Fig. 2, the piston, in the meantime, having completed its inward stroke. Coincident with this movement of the piston 32, the arm 204, on the cross-head, compresses the spring 200, on the other end of the tube 185, and forcing 30 the end of the tube within the shock-absorber 186, the catch 220, in the collar 218, moving over and engaging with the catch pin 216, on the yielding plate 209, 35 hence the movement of the tube 185 is checked. Simultaneously with the inward piston movement, the arm 150, on the cross-head block 137, moves the sliding lug 148 into contact with the head 147, on the stem 146, drawing upon said stem, and consequently the plate 144, having the catch pin 145, in the direction of the cylinder 105, until the catch pin 154, on the pivoted plate 150, which moves downwardly upon the 40 withdrawal of the trip 150°, engages with the catch pin 145, on the plate 144, and the plate 144 is locked in position thereby. In this movement of the plate 144 the position of the crank arm 38, on the water cock, 45 is reversed in position, cutting off the supply of water to the vacuum tank and moving said crank arm into the position seen in dotted lines in Fig. 2. In the movement described of the piston 52, the steam valve 50 116, in its movement toward the outer head 106, of the cylinder 105, comes into contact with the valve 115, and both move in unison, cutting off the supply of steam through the ports 112, 113, until a reverse movement, 55 or the movement of the piston 52 in the direction of the head 51°, takes place, in which movement the reverse action of the reciprocating tube 185 takes place, and is held as in the first instance described, by the 60 catch pin 206, on the yielding plate 209.

In this reverse movement of the piston 52, the plate 144 being locked in position, the movement of the lug 148 against the spring imparts tension thereto, the trip plate 150 immediately engaging beneath the catch 70 plate 152, releasing the catch pin 154 from engagement with the catch pin 145, on the sliding plate 144, and said plate recoils against the head plate 51°, to the cylinder 51, and bringing the head 147, on the stem 75 146, which has projected a short distance beyond the lug, in contact with the lug, and reversing the position of the pivoted bar 156, and moving the crank arm 38 into the position for admitting water to the vacuum 80 chamber. The operations, as described, are repeated until the repeated supply of steam and the condensation is sufficient to effect a vacuum in the vacuum tank, and produce a suction on the diaphragm 228, of the 85 vacuum controller, and cause a collapsing movement thereof, sufficient to compress the spring 235, and draw down the pivoted end of the arm 222 and cause the engagement of the catch pin 224, with the catch pin 219, 90 on the collar 218, on the reciprocating tube 185, thereby causing the action of the tube to cease, and also the crank arm 94, controlling the water supply to the motor. When the steam has condensed in the 95 vacuum 161, the water of condensation passes through the same supply pipe 162, to the pipe 127, until subsequently discharged through the steam valve into the vacuum tank. The volatile liquid container 106, 100 becoming cooled, collapses, and under the compression of the spring 176, the bar 177 moves downwardly, bringing the catch plate 182 in the path of movement of the arm 204, on the cross head block 137, and upon the 105 reverse action of the piston 52, of the hydraulic motor, the arm 204 moves in the sliding bar 100, so as to close the valve 77, in the valve box 70, and the action of the 110 hydraulic motor ceases. The receiver 161 is receiving the supply of steam at all times from the generator, and, consequently, upon a break in the vacuum in the vacuum tank the motor resumes action automatically until the vacuum is complete, and the controlling lever 222 checks the reciprocations of the tube 185, and the valve action of 115 water valve 86 ceases.

The apparatus affords means for producing a vacuum under a force of high or low 120 steam pressure, and with rapid condensation, so that at all times the steam admitted to the radiators is employed with a higher degree of efficiency than heretofore.

The invention is adapted to the use of exhaust steam, where the live steam is employed for generating power, and the means for producing reversing movements adapted to various kinds of motors.

Instead of employing the volatile liquid- 130

5 container, as described, a thermostat, as seen in Fig. 14, may, if desired, be substituted, the receiver in this instance comprising a hermetical vessel 245, the bottom plates 246 being inclined downwardly, from the ends 247, 248, of the receiver, to a point forming a V-shaped bottom. Side plates 249 are connected with the end plates 247, 248, and a top plate 251 is hermetically connected 10 with said side and end plates. Upon said top plate 251 are placed the thermostat, composed of thin plates 252, 253, of different metals, of different expansibility and of the same size as the top plate 251. These 15 thermostat plates are united together, and secured to the receiver by a transverse bar 254, attached to one end of said receiver.

20 A flat plate 255 is rigidly connected with one side plate 249, of the receiver, and by 25 means of which the receiver is bolted to the outer flange of the cylinder head 107, of the cylinder 105. A supply pipe 256 extends through the plate 254, into the receiver, and is connected with the steam supply pipe 162. 25 With the upper plate 252, of the thermostat, is connected a short horizontally-extended plate 256, the outer end being forked at 257, and with said forked end is pivotally connected the upper end of a bar 258, 30 which is the same as the bar 177, on the receiver 161, the lower end of the bar having an opening 259, for the reception of the sliding bar 100, operating the valve 77, in the water valve box 70.

35 The invention affords unlimited power for operating all valves for either steam or water, there being no dead centers to cause stoppage of the water. The live steam which is fed to create a vacuum in the vacuum tank and which expands within the cylinder 105, and thereby passes to the vacuum tank in a large volume, and without subjecting the tank to the high steam pressure of the steam generator in other 40 steam vacuum reproducing systems, the action of the vacuum extending to the generator. The water of condensation in the vacuum tank 24 is discharged from the tanks through the pipe 28, past the check 45 valve 27, and through trap 26*, and thence to the sewer through pipe 34.

50 The variability of vacuum force within the vacuum tank, when the vacuum is formed, and which is requisite for checking the action of the hydraulic motor is controlled by the adjusting nut 234, on the stem 232, in connection with the diaphragm 233, on the vacuum controller or generator 225, the condensation of steam which may follow 55 with or without the spray of water under low temperatures surrounding the tank, and the expansion of the steam becomes materially of service and of importance, in order to effect the rapidity of condensation 60 of the steam.

It is evident that other radiators in a steam heating system are connected up with the steam pipe, in a similar manner, the air pipes being similarly connected with the pipe connection 42. It is also evident that 70 instead of the radiators, a system of steam radiating pipes may be employed for the steam, and arranged in any manner preferred, the application of the invention being obviously as efficient as in the use of the 75 radiators 20, and the independent pipe 129 may be supplied with exhaust steam from any suitable source, if desired, in which case the valve 129* will be closed and the steam supplied independently of the generator, and from any suitable source.

Various changes in the construction and arrangement of the several parts of the invention may be made, and such other modifications employed as are within the scope 85 of the appended claims.

Having fully described my invention, what I now claim as new and desire to secure by Letters Patent is:

1. In a vacuum producing and maintaining apparatus, the combination with a closed vacuum tank, a supply pipe having a suitable source of supply of the heating medium leading to said tank, an air pipe leading within the said tank, and with a valve in 90 the supply pipe for the heating medium of a fluid pressure operated device having a source of fluid supply independent of the heating medium for controlling said valve.

2. In a vacuum producing and maintaining apparatus, the combination with a closed vacuum tank, a steam supply pipe having a suitable source of steam supply leading to said vacuum tank, and an air pipe leading within the said tank, of a heat expanded and 100 controlled regulator in operative relation with the steam pipe, a valve controlling the passage of the steam to the vacuum tank, a motor controlling the opening and closing of 105 said valve, a vacuum controlled governor in communication with and controlled by the force of the vacuum within said tank acting to control the movement of said motor upon a maintenance of a vacuum within the said tank, and means controlled by said heat expanded regulator to start and stop the 110 action of the motor.

3. In a vacuum producing and maintaining apparatus, the combination with a steam condensing closed tank, a steam supply pipe 115 having a suitable source of steam supply leading within said tank and a steam supply valve, a valve cock for delivering the water within the condensing tank, means co-acting to open and close said steam supply valve 120 and said valve cock at predetermined intervals independent of the steam heat or pressure of the steam.

4. In a vacuum producing and maintaining apparatus, the combination with a steam 130

condensing tank, a steam supply pipe having a suitable source of steam supply leading within said tank, a valve controlling the flow of the steam and with an air pipe leading within the said steam condensing tank, of a fluid pressure operated device having its source of supply independent of the steam supply pipe and mechanism actuated thereby co-acting to open and close said steam and water valves at predetermined intermissions.

5. In a vacuum producing apparatus, the combination with a closed vacuum tank for steam condensation and with means for supplying steam to said tank, a steam supply valve, a pipe for the admission of air leading within the vacuum tank of mechanism co-acting with the steam and air valves to open and close said valves, a motor co-acting with said mechanism, motor starting means, and a steam controlled thermo-dynamic regulator actuating the starting means to said motor.

6. In a vacuum producing apparatus for steam heating systems, the combination with a closed vacuum tank, a steam pipe having a suitable source of steam supply leading within said tank, a steam supply valve and an air pipe leading within the said tank a water valve cock leading within the said tank, and a water supply pipe leading from a suitable water supply under pressure to said cock, a water motor, and valve operating mechanism for said steam valve controlled by said motor, and a steam controlled regulator for the initial starting of the water motor.

7. In a vacuum producing and maintaining apparatus for withdrawing the air from the steam pipes in steam controlling systems, the combination with a vacuum tank, a steam pipe having a suitable source of steam supply leading within said tank, and a valve controlling the supply of steam to said tank, and a water valve cock leading within said tank, and a water supply pipe leading from a source of water supply under pressure to said cock, a water motor actuated by and in communication with said water pipe controlling the opening and closing of the water and steam valves, and a governor controlled by the maintenance of the vacuum within said tank controlling the action of the water motor.

8. In a vacuum producing and maintaining apparatus for withdrawing the air from the steam pipes in a steam heating system, a closed vacuum tank, and check-controlled discharging means for the water of condensation, of means for supplying steam to said tank, comprising a valve cylinder, an outer cylinder inclosing the valve cylinder having a steam chamber between the cylinders, and a steam supply pipe connected with the valve cylinder, a piston rod, and movable and fixed piston valves on said rod, said

valve cylinder having ports discharging the steam within the steam chamber, a combined steam and air pipe leading from the steam chamber within the vacuum tank, means for supplying steam to the valve cylinder, and means for actuating the piston valve rod at predetermined intermissions.

9. In a vacuum producing and maintaining apparatus for withdrawing the air from the steam pipes in a steam heating system, the combination with a closed vacuum tank, and check-controlled discharging means for the water of condensation, of means for admitting the steam to the vacuum tank for condensation comprising an outer steam cylinder having heads, and an inner valve cylinder connected with said heads, said cylinders having an expansion steam chamber between, said cylinder heads having an opening for the admission of the steam to the valve cylinder, and a piston rod extending through the other cylinder head, movable and fixed piston valves on said piston rod, said valve chamber having ports leading within the steam chamber between the cylinders, a combined steam and air pipe leading from the steam chamber between the cylinders within the vacuum tank, means for conducting steam to the opening in the valve chamber, and a motor operating the piston valve rod.

10. In a vacuum producing and maintaining apparatus for withdrawing the air from the steam pipes, in steam heating systems, the combination with a closed vacuum tank, and check-controlled discharging means for the water of condensation, of means for admitting the steam at intermissions within the vacuum tank, comprising an outer steam cylinder having heads, and an inner hollow cylinder supported by said heads, said cylinders having a chamber between for the expansion of the steam, and said inner cylinder having ports intermediate the ends thereof leading within said steam expansion chamber, a piston valve rod within the valve cylinder and extending through one of said heads, and movable and fixed piston valves on said rod, and a steam supply pipe having a suitable source of steam supply extending through the other cylinder head, in communication with the valve chamber, a steam supply pipe leading from the steam chamber between the said cylinders within the vacuum tank, and means for operating the piston rod at predetermined intermissions.

11. In a vacuum producing and maintaining apparatus for withdrawing the air from the steam pipes in steam heating systems, the combination with a closed vacuum tank, and check-controlled discharging means for the water of condensation, of means for controlling the admission of steam for condensation and water to the vacuum tank for rapid condensation, comprising an outer

steam cylinder having heads and a hollow inner valve cylinder connected with said heads, said cylinders having a chamber between for the steam, and said inner cylinder having ports leading within the steam chamber, a piston valve rod within the valve cylinder extending through one of said heads, and a steam supply pipe having a suitable source of steam supply leading through the 5 other cylinder head and in communication with the said valve cylinder, movable and fixed piston valves on said valve rod within said valve cylinder, an air pipe leading within the tank, and a steam pipe leading from 10 the steam chamber between said cylinders within said vacuum tank, a water pipe leading to the vacuum tank, and a valve controlling the supply of water for condensation of the steam to said tank, and means acting 15 automatically at predetermined periods to operate the piston valve rod and open and close the water valve.

12. In a vacuum producing and maintaining apparatus for controlling the admission of steam and water to closed vacuum tanks for rapid steam condensation, the combination with a closed vacuum tank, a steam supply pipe having a suitable source of steam supply, and a valve controlling the 20 supply of steam to the tank, a water supply pipe leading to the said tank, and a valve controlling its discharge within the tank, reciprocating valve-operating mechanism acting to open and close the steam supply valve 25 at predetermined periods, and independent locking mechanism for the water valve released automatically by the reciprocating steam valve operating mechanism.

13. An apparatus for producing and 30 maintaining the vacuum in steam heating systems, comprising a closed vacuum tank, means for supplying steam and water to said tank for steam condensation, and suitable valves controlling the admission of the 35 steam and air to said tank, a motor and valve operating mechanism actuated by said motor, and a self-acting motor controlling device controlled by the valve operating mechanism and acting intermittently to 40 control the movement of the motor.

14. An apparatus for producing and maintaining the vacuum in steam heating systems, comprising a closed vacuum tank, means for supplying steam and water to 45 said tank for steam condensation, and a fluid pressure valve controlled motor, mechanism operated by the motor to alternately open and close the steam and water valves, and self-acting mechanism controlled in its 50 movement by the valve operating mechanism acting reciprocally to control the motor valve.

15. An apparatus for producing and maintaining the vacuum in steam heating 55 systems, comprising a closed vacuum tank,

steam and water valves for supplying steam and water to said tank for steam condensation, and steam and water valves controlling said supply, reciprocating power-propelled valve operating mechanism acting to open 70 and close said steam valve, and spring-actuated locking means for locking said water valve in a movement in the direction of the valve operating mechanism and released by said mechanism in a movement in an opposite direction. 75

16. An apparatus for producing and maintaining the vacuum in steam heating systems, comprising a closed vacuum tank, suitable valves for supplying steam and 80 water to said tank for steam condensation, a vacuum governor in communication with and controlled by the vacuum in said tank, a water power-propelled reciprocating valve operating mechanism acting to open 85 and close said steam and water valves, and a spring-actuated reciprocating device controlling the movements of the valve-operating mechanism, and a pivoted lever controlled by the vacuum governor and governing the movement of the spring-actuated reciprocating device. 90

17. An apparatus for producing and maintaining the vacuum in steam heating systems, comprising a closed vacuum tank, 95 suitable steam and water valves for supplying steam and water to said tank for steam condensation, a spring-controlled vacuum governor in communication with and controlled by the vacuum within the tank, a power propelled reciprocating valve operating mechanism acting to open and close said steam supply valve, and spring-actuated reciprocating means controlling the movement of the valve operating mechanism, and spring-actuated locking means co-acting with the valve controlling mechanism to move and lock said water valve in an open position and automatically release said locking means in a movement to close 100 said valve. 110

18. An apparatus for producing and maintaining the vacuum in steam heating systems, comprising a closed vacuum tank, suitable valves for supplying steam and water to said tank for steam condensation, a vacuum governor in communication with and controlled by the vacuum within said tank, reciprocating valve operating mechanism acting to open and close said steam valve, a spring-actuated reciprocating tube co-acting with and controlled in reciprocation by the valve operating mechanism and acting to control the movement of said mechanism, a pivoted controlling lever controlled by the vacuum governor at one end, and engaging means upon the reciprocating tube and at the other end of said lever. 115 120 125

19. An apparatus for producing and maintaining the vacuum in steam heating 130

- systems, comprising a closed vacuum or tank, and suitable valves for controlling the admission of steam and water to said vacuum tank for steam condensation, comprising a piston operated fluid, a cylinder, and a piston controlled valve cylinder, piston rods for controlling the pistons in the respective cylinders, and a cross-head connected with said rods, valve controlled means for controlling the supply of the fluid under pressure to the fluid cylinder, and means for supplying the vacuum tank with steam through the piston valve, a valve cock leading within the vacuum tank, and means for supplying water thereto, mechanism acting automatically to control the admission of the fluid to the fluid piston-operated cylinder, and means on the cross-head controlling the water-supplying mechanism.
- 10 20. An apparatus for producing and maintaining the vacuum in steam heating systems, comprising a closed vacuum tank, a piston operated valve cylinder, and valve admitting the fluid under pressure thereto, and a piston-operated valve cylinder admitting steam thereto, piston rods operating said fluid actuated, and valve piston connected therewith, and a cross-head connected with said piston rods, a reciprocating tube having a longitudinal opening therein, and expansion springs therein, shock absorbers for the ends of said tube, means connected with the said tube for operating the valve to the fluid actuated cylinder, means 30 on the cross-head engaging with and compressing alternately said springs, and locking and releasing devices carried by the cross-head acting to hold and release the said reciprocating tube at the end of a reciprocating tube movement.
- 35 21. An apparatus for producing and maintaining the vacuum in steam heating systems, comprising a closed vacuum tank, a piston operated valve cylinder and valve admitting the fluid under pressure thereto, and a piston operated valve cylinder admitting steam thereto, means for conducting steam to said cylinders and from thence to said tank, piston rods connected with the 45 respective pistons, and a cross-head connected with said piston rods, a reciprocating tube having a longitudinal opening therein, and expansion springs in said tube, shock absorbers for the ends of said tube, means connected with said tube for operating the valve to the fluid-actuated cylinder, means on the cross-head engaging with and compressing alternately said springs in the reciprocating tube, locking means on the said 50 tube and cross-head acting to hold the tube at the end of a tube reciprocating movement and release said tube in a reverse movement of the cross-head, a water supply valve cock leading within the tank, a pivoted operating lever connected therewith, and a fixed tube
- 60 65

having a longitudinal opening, a spring-actuated sliding plate operating the valve-controlling lever and controlled by the cross-head in its movements.

22. An apparatus for producing and maintaining the vacuum in steam heating systems, comprising a closed vacuum tank, a piston-operated valve cylinder, and a rotary valve admitting fluid to said cylinder under pressure, and a hollow cylinder for steam, and connecting plates for said cylinders, a piston valve in said steam cylinder, a steam pipe leading within the vacuum tank in communication with said valve cylinder, piston rods connected with the respective pistons, and a cross-head connected with the piston rods, a reciprocating tube having a longitudinal opening therein, and expansion springs in said tube, a lug operable between said openings, suitable supporting and yielding means for said reciprocating tube, and means on said reciprocating tube connected with and operating the rotary valve on the fluid-operated cylinder, a bar in the cross head connected with the lug on said reciprocating tube, locking means on said tube and said connecting plates for the cylinders acting to hold the tube at the end of a reciprocating movement, and means on the cross-head acting to release said tube in a reverse movement of the cross-head, a water supply cock leading within the tank, and a pivoted operating lever connected therewith, a fixed tube having a longitudinal opening, a spring actuated sliding plate operatively connected with the lever operating the water valve, means on the cross-head operating the sliding plate in said tube, locking means for said sliding plate, and releasing means on the cross-head, a valve box and valve on the fluid operated piston cylinder, an arm controlling said valve, a spring-actuated recoiling bar connected with the arm on the valve in the valve box, and an arm on the cross-head, and a lug on the said recoiling bar with which the said arm comes normally into contact and opens the valve, and a thermodynamic apparatus controlled by the heat of the steam adapted to raise the free end of the said valve operating bar.

23. In a valve operating mechanism for the valves to vacuum tanks for steam condensation, the combination with a fluid motor cylinder and piston, of a steam valve and cut-off connecting plate rigidly connecting said cylinder, and cut-off in alignment with each other, piston rods operating said piston and steam cut-off, and a cross-head connected with said piston rods, a rotary valve casing having ports, and a rotary valve acting to control the admission of the fluid to each end of the cylinder and exhaust the same, means for supplying the fluid under pressure to the valve casing, and an inde-

pendent spring-actuated reciprocating valve controlling member, and connecting devices connected therewith and with said rotary valve, means on the cross-head controlling the reciprocations of said valve controlling member, self-engaging means on said member and the connecting plates for the cylinder, and steam cut-off and disengaging means therefor, and cross-head acting to permit of a recoil of the valve controlling member independently of the reverse movement of the cross-head.

24. In a valve operating mechanism for the valves to vacuum tanks for steam condensation, the combination with a fluid motor cylinder and its piston, of a steam valve cut-off piston rod operating said piston, and said steam cut-off connecting piston connecting said cylinder and said steam cut-off in alinement with each other, and an arm connected with the cross-heads, a valve casing, and a rotary valve having ports admitting the fluid to each end of the cylinder and exhausting the same, a reciprocating valve operating closed tube having an opening therein, and a plunger within the tube with which the arm on the cross-head is connected, expanding and contracting springs within the tube which are alternately contracted by the said plunger, spring-actuated engaging devices on the connecting plates for the cylinder and steam cut-off, and said reciprocating tube co-acting to hold the tube at the end of a reciprocating movement, and a releasing device on the cross-head acting to release said tube holding devices in a reverse movement of the cross-head, whereby the rotative valve on the fluid cylinder receives an initiative movement to change the position of the valve ports in advance of the movement of the cross-head.

25. In valve operating mechanism for the valves to vacuum tanks for steam condensation, the combination with a fluid motor cylinder and piston, of a steam valve cut-off cylinder, and piston valve-connecting plates connecting said cylinders in alinement with each other, a steam pipe connected with said valve cylinder, a valve casing on the fluid motor cylinder, and a rotary valve having ports which admit the fluid into each end of the cylinder alternately and exhaust the same, a reciprocating valve operating tubular member, and supporting means therefor, on one of the connecting plates for said cylinder, spring actuated pivoted plates on said cylinder, connecting plates having engaging devices on their free ends, and corresponding devices on said tubular member, upwardly-extending pins on said free ends of the tube engaging devices, and a fixed tripping member on the cross-head adapted to contact with said pins and release said tube engaging member.

26. In valve operating mechanism for the

steam and water valves to vacuum tanks, the combination with a fluid operated motor cylinder, and piston and steam cut-off, and with connecting plates connecting said cylinder and cut-off in alinement with each other, and with piston rods operating said piston and steam cut-off, and a cross-head connected with the said pistons, a valve casing and valve on said fluid operated cylinder, and with means for operating said valve, of a water valve, and a reciprocating valve opening and closing member acting to open and close said water valve, and a catch on said member, and a spring-actuated pivoted catch member connected pivotally with the connecting plates for said cylinder and steam cut-off and adapted to lock said reciprocating valve closing member in position, and a releasing device on the cross-head adapted to release said pivoted catch member in the reciprocation of the cross-head.

27. In valve operating mechanism for the steam and water valves to vacuum tanks, the combination with a fluid operated motor cylinder and piston and a steam cut-off, and with connecting plates connecting said cylinder and cut-off in alinement with each other, and with piston rods operating said piston and steam cut-off, of a cross-head connected with said pistons, a valve casing and valve on said fluid operated cylinder, and means for supplying the fluid under pressure thereto, means for operating said valve, and a water valve casing and valve, a fixed tube having longitudinal openings therein, a spring-actuated sliding plate in said tube, means connected with said plate and water valve to close said valve in one movement of the sliding plate, and means controlled by the cross-head for imparting a reverse movement to said sliding plate to open said water valve.

28. In a valve operating mechanism for the steam and water valves to vacuum tanks, the combination with a fluid operated motor cylinder and piston, and a steam cut-off, and with connecting plates connecting said cylinder and steam cut-off in alinement with each other, piston rods operating said piston and cut-off, and a cross-head connected with said piston rods, a valve casing and valve on the fluid operated cylinder having ports, and means for supplying said fluid operating cylinder with fluid under pressure, and means for operating the valve in the valve casing, a fixed tube having longitudinal openings, and a sliding valve controlling plate within said tube, a water valve operatively connected with said plate, a perforated sliding lug in said tube, and a rod connected with the sliding plate and extending through the perforation in said lug and provided with a head at its outer end, an expanding and contracting spring within

- said tube bearing against said lug and said sliding valve controlling plate, and an arm on the cross-head operatively connected with the sliding lug in said case.
- 5 29. A valve operating mechanism for the valves to vacuum tanks, comprising a stationary tube having longitudinal openings therein, a sliding valve operating member provided with an inclined catch pin, and a 10 sliding lug having an opening, and a rod connected with said sliding plate and extending through said lug and provided with a head, an expanding and contracting spring within said tube bearing against said 15 plate, and said sliding lug, and a reciprocating member, and an arm on said member having its outer portion connected with said lug, a pivoted plate having an inclined catch pin thereon, and a tripping arm on 20 the reciprocating member adapted to raise said pivoted plate in a movement toward said plate of the reciprocating member.
30. A valve operating mechanism for the water valves to vacuum tanks, comprising a 25 stationary tube having longitudinal openings therein, a sliding valve operating plate within said tube having an inclined catch pin, a sliding lug within said tube, and an arm of the reciprocating member yieldingly 30 connected with said lug having an opening extending therethrough, a rod connected with said sliding valve operating plate having a lug on its free end, an expanding and contracting spring within said tube bearing 35 against said valve operating plate and said lug, a spring-controlled pivoted plate having an inclined catch pin in the path of the pin in said sliding plate, and a releasing device on the reciprocating member in the 40 path of the spring controlled pivoted plate.
31. A valve operating mechanism for the water valve to vacuum tanks, comprising a stationary tube having longitudinal openings therein, a sliding valve operating plate 45 within said tube having a lug extending through one of said openings, and a pivoted valve operating lever pivotally connected with said lug, said plate having an inclined catch pin extending through the 50 other longitudinal opening, a sliding lug having an opening within said tube, a reciprocating member, and an arm on said member having its free end yieldingly connected with said lug, a contracting and ex- 55 panding spring within said tube bearing upon said valve operating plate and said sliding lug, and a rod connected fixedly with said valve operating plate and extending through the opening in said lug and pro- 60 vided with a head, a pivoted catch plate having an inclined catch pin in the path of the pin on said sliding valve operating plate and adapted to be held thereby in the movement of the reciprocating member, and 65 a plate-releasing extended plate on the re-
- ciprocating member for releasing said catch pins and permitting of the expansion of said spring.
32. In mechanism for rapid liquid valve discharge movement, a reciprocating member, an arm extending in one direction, and a releasing device or plate in the other direction, a stationary tube having a longitudinal opening, a sliding plate therein, and an inclined catch pin thereon extending through said opening, a sliding lug yieldingly connected with the lug on the arm on the sliding member having an opening extending therethrough, a rod connected with the sliding plate and extending through the opening in said lug and having a head upon its free end, an expanding and contracting spring within said tube bearing at one end against said sliding plate and at the other against said sliding lug, a pivoted spring controlled and inclined catch pin thereon in the path of the catch pins on the sliding plate in said tube adapted to hold said sliding plate during the compression of said spring, and releasing device for said catch plate.
33. In valve operating mechanism for the steam and water valves to steam condensing vacuum tanks, the combination with a fluid operated motor and piston, of an outer steam cylinder having heads, and connecting devices for said motor and steam cylinder, an inner steam cylinder cut-off connected with said heads and having a chamber for steam between said outer and inner cylinders, said inner steam cylinder cut-off having ports leading to said steam chamber, a steam pipe connected with the outer cylinder, and piston rods in the respective cylinders, a fixed and movable piston valve on said steam cut-off cylinder and a cross head connected with said piston rods, a valve casing and valve on the fluid motor cylinder, and a water valve casing, and spring actuated recoiling devices connected with the water valve, and releasable locking devices therefor and acting independently of the cross-head to actuate the water valve at each discharge of the steam through the steam ports.
34. In vacuum tanks for steam condensation, the mechanism for operating the water and steam valves, comprising a fluid operated motor cylinder, and piston, and piston rod, and an outer steam cylinder having heads, connecting plates connecting said cylinders in alignment with each other, a steam cut-off cylinder within the outer steam cylinder connected with the heads of said outer cylinder and having a chamber for the steam between said outer and inner cylinders, and ports in said inner cylinder leading into said steam chamber, a piston rod within said inner steam cylinder, and fixed and movable piston valves on said rod acting to discharge the steam through the ports in one

direction of the valve movement, and a discharge pipe for the steam leading from the other cylinder, a cross-head connected with the piston rods, a water valve casing and 5 valve, a spring retracted valve controlling device on the vacuum tank, and locking means therefor controlled by the cross-head, and releasing means on the cross-head therefor whereby the rapid discharge of the water 10 from the water valve is coincident to a discharge of the steam from the steam discharge pipe.

35. In vacuum tanks for steam condensation, the mechanism for operating the water 15 and steam valves, comprising a fluid operated motor cylinder and piston, and piston rod, and an outer steam cylinder having heads, and an inner steam cylinder or cut-off connected with said heads and having a 20 concentric steam chamber between said outer and inner steam cylinder, connecting plates connected with the respective fluid operated and outer steam cylinders, a piston rod with-

in the inner steam cylinder, and fixed and movable piston valves on said rod, said cylinder having ports intermediate the ends of the cylinder for the discharge of steam into the steam chamber in one direction of movement, a cross-head connected with said piston rods of the respective fluid operated 30 and steam cylinders, a water valve casing and valve, a spring-controlled locking device actuating the water valve, an arm on the cross-head acting to move said locking device into a locking position, and a releasing 35 device on the cross-head acting to release said spring-controlled locking device upon the movement of the cross-head to operate the steam valve in the steam cylinder for a 40 discharge of the steam through the steam ports.
